The ornamental design for a brake caliper hardware set, as shown and described.

DESCRIPTION

FIG. 1 is a front isometric view of one part of a brake caliper hardware set in accordance with the new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a left side elevational view thereof; and

FIG. 7 is a right side elevational view thereof.

FIG. 8 is a front isometric view of a second part of the brake caliper hardware set;

FIG. 9 is a front elevational view thereof;

FIG. 10 is a top plan view thereof;

FIG. 11 is a rear elevational view thereof;

FIG. 12 is a bottom plan view thereof;

FIG. 13 is a left side elevational view thereof; and

FIG. 14 is a right side elevational view thereof; and,

FIG. 15 is an isometric view of the brake caliper hardware set illustrated in FIGS. 1-14, shown as positioned in a brake caliper with brake pads.

The broken lines shown in FIGS. 1, 2, 4-9 and 11-14 illustrate portions of the brake caliper hardware set that form no part of the claimed design. The broken lines shown in FIG. 15 illustrate environmental structure of brake caliper and brake pads associated with the brake caliper hardware set and form no part of the claimed design.
